[57] CLAIM

The ornamental design for a condiment shaker, as shown and described.

DESCRIPTION

FIG. 1 is a top, front perspective view of a condiment shaker showing my new design, the three remaining sides being the same as the front;

FIG. 2 is a front elevation view thereof, the broken line showing of the athlete being for illustrative purposes only and forming no part of the claimed design;

FIG. 3 is a top plan view thereof; and,

FIG. 4 is a bottom plan view thereof.
